C. E. ALLEN

ANCHOR

Filed Dec. 24. 1924

INVENTOR
CLAUDE E. ALLEN.

BY Peter Vaughan ATING.

UNITED STATES PATENT OFFICE.

CLAUDE EDWIN ALLEN, OF MONCTON, NEW BRUNSWICK, CANADA.

ANCHOR.

Application filed December 24, 1924. Serial No. 757,850.

To all whom it may concern:

Be it known that I, CLAUDE EDWIN ALLEN, a subject of the King of Great Britain, and resident of Moncton, in the Province of New 5 Brunswick and Dominion of Canada, have invented certain new and useful Improvements in Anchors, of which the following is a specification.

This invention relates to improvements 10 in anchors and the objects of the invention are to provide a collapsible anchor adapted to fold flat and to consequently occupy much less space when not in use.

Further objects are the provision of an 15 anchor of this description provided with a ring adapted to slide freely from end to end of the arm so that the anchor will grip securely no matter how it is thrown out.

Further objects are the provision of an 20 anchor which will not foul and which, no matter how entangled the rope may become, cannot let go. Furthermore, being provided with a fluke in each end, should the boat twist around so as to twist the rope around one 25 end, the other fluke will take hold.

A still further object is the provision of an anchor which can be easily raised even 30 when embedded in hard brick clay. With an ordinary anchor some difficulty is often encountered when attempting to raise it while with my improved anchor the boat may be steered in the opposite direction and as the ring will slide to the other end of the arm 35 the anchor will be raised without difficulty as the embedded fluke will come out in the same direction as it went in, making it unnecessary to tear its way through.

With the foregoing and other objects, hereinafter more fully described, the invention 40 consists essentially of a collapsible anchor comprising a central cylindrical portion having fixedly secured therein at one end an anchor member and slidably secured therein, at the other end, a second anchoring member and means for retaining it in 45 position when adjusted.

Referring now to the drawings in which like characters of reference indicate corresponding parts in each figure.

50 Figure 1 is a plan view of my improved anchor with one anchoring member at right angles to the other.

Figure 2 is a similar view showing both anchoring members in parallel alignment.

55 Figure 3 is a longitudinal section.

Figure 4 is a section on line 2—2 of Figure 3.

In the drawings, A designates an example of my improved anchor as a whole comprising a tubular member 10 having integral 60 therewith an anchoring member 11 of well known construction and formed with the flukes 12 and 13. 14 is a second and separate anchoring means adapted to fit into and to slidably engage with the other end 65 of the tubular member 10. To prevent the anchoring member 14 from becoming disengaged with the tubular member I provide in the tubular member a curved slot 15 adapted to engage with a pin 16 carried by 70 the stem 17 of the member 14, while between the end of the stem 17 and the end of the tubular member 10 is arranged a spiral spring 18 designed to automatically retain the member 14 in an outwardly extending 75 position. Adapted to travel between the two anchoring members, on the member 10, is a ring 19 to which is attached a link 20 to which the cable is attached to connect the latter with the boat. 22 is an orifice to 80 allow for lubrication of the interior of the tubular member 10 and the spring 18.

From the foregoing it will be seen that when the anchor as a whole is shipped, the member 14 can be moved inwardly, the pin 85 16 engaging with a recess 21 in the top of a slot 15 permitting the anchor as a whole to lie flat as shown in Figure 1.

Furthermore as designed the adjustable anchoring member 14, before being thrown, 90 can be set at right angles to the fixed anchoring member 13 so that no matter what way the anchor is thrown it will grip, as shown in Figure 1. 23 is the hole for removing pin 16 when taking the anchor apart. 95

As many changes could be made in the above construction and many apparently widely different embodiments of my invention, within the scope of the claims, constructed without departing from the spirit 100 or scope thereof, it is intended that all matter contained in the accompanying specification and drawings shall be interpreted as illustrative and not in a limiting sense.

What I claim as my invention is:

1. A collapsible anchor comprising a tubular arm formed with an anchoring member at one end and adapted to slidably engage with a turnable anchoring member at the other end. 105

2. The device as claimed in claim 1, in which spring actuating means are arranged in the tubular arm for the turnable anchoring member.
- 5 3. The device as claimed in claim 1, in which the tubular member is provided with a slot having a recess therein to engage with a pin carried by the adjustable anchoring member.
- 10 4. An anchor of the character described comprising an anchor member formed with a tubular shank having a second anchoring member adapted to operatively engage with said shank, spring actuating means for the second anchoring member and means for retaining the said member in an adjusted posi-

tion, a ring adapted to travel on said shank between the anchoring members and a link connecting the ring with a cable.

5. A double anchor formed with a fixed 20 anchoring head and a spring actuated adjustable anchoring head and means for retaining the adjustable head in adjusted position and a ring member adapted to travel between said heads. 25

In witness whereof I have hereunto set my hand in the presence of two witnesses.

CLAUDE EDWIN ALLEN.
